E. M. WAYLAND

ADJUSTING MECHANISM FOR FRUIT GRADING MACHINE KICKER WHEELS

Filed Feb. 8, 1927

UNITED STATES PATENT OFFICE.

EDWIN M. WAYLAND, OF COVESVILLE, VIRGINIA.

ADJUSTING MECHANISM FOR FRUIT-GRADING-MACHINE KICKER WHEELS.

Application filed February 8, 1927. Serial No. 166,740.

This invention relates generally to that type of fruit grading machines including a plurality of kicker wheels disposed in predetermined spaced position with respect to the usual sizing belt for so engaging the fruit as to kick the same from the sizing belt to the distributing belt, the invention having more specifically to do with means whereby the kicker wheels may be moved and maintained in predetermined spaced position with respect to the sizing belt.

One of the primary objects of the invention is to provide an adjusting device of this character that may be readily installed in this general type of fruit grading machinery without requiring any unusual alterations or expenditure and without in any manner whatever affecting the satisfactory operation of such type of machine.

With the foregoing and other objects in view as the nature of the invention will be better understood, the same comprises the novel form, combination and arrangement of parts hereinafter more fully described, shown in the accompanying drawings and claimed.

In the drawing wherein like reference characters indicate corresponding parts throughout the several views:

30 Figure 1 is a view in fragmentary diagrammatic section of a kicker wheel type of fruit grading machine showing in side elevation and partly in cross section my improved kicker wheel adjusting mechanism.

35 Figure 2 is a vertical section taken substantially upon the line 2—2 of Figure 1, and

40 Figure 3 is a longitudinal section through the clevis of the adjusting means and taken substantially upon the line 3—3 of the same figure.

First having reference to that structure of a conventional kicker wheel fruit grader disclosed in dotted lines. A designates one of

45 the usual vertical wooden posts of the machine frame, while B designates the sizer belt supporting decking that is usually inclined in a transverse direction as disclosed and over which moves the usual sizer belt C.

50 At the edge of this decking B remote from the post A is an oppositely inclined wider decking D over which travels the distributing belt E of the grading machine. This character of grader also includes a plurality

55 of longitudinally spaced circular kicker

wheels 5 disposed upon a common rotating shaft 6 suitably operated and arranged above the sizer belt C and slightly inwardly thereof.

My particular adjusting mechanism consists of an angle plate 7 having a pair of openings in the top wall thereof adjacent the opposite ends so as to permit the securing of this plate to the usual horizontal wooden frame bar of the machine, not shown, by bolt and nut connections 8—8. Rigidly secured to the depending wall of this angle plate is a depending relatively triangular shaped metallic plate 9 to the lower end of which is pivotally secured as at 10 an elongated lever 11 preferably of flat bar-like configuration, the forward end of which is of slightly downwardly converging relation with respect to the major length of the lever as clearly indicated in Figure 1, and through the forward end of which extends the kicker operating shaft 6 and preferably directly adjacent one of the kicker wheels as more clearly disclosed in the sectional view, Figure 2.

The side wall of the angle plate 7 terminates at the rear end inwardly of the rear end of the top wall as indicated in Figure 1 and disposed through an opening in the end of the top wall of said plate is a threaded eye bolt 12 to the lower eyed end of which is pivoted as at 13 a depending clevis 14. As clearly disclosed in Figure 3, this clevis consists of a pair of narrow plates 15—15 maintained in spaced relation at their upper ends by the disposition of the eyed end of the bolt 12 therebetween and at their lower ends by spacing member 16 secured to the plates by cross rivets 17.

Threaded upon the eye bolt 12 beneath the angle plate 7 is a lock nut 18, while threaded upon the upper end of said bolt is a wing nut 19 for a purpose hereinafter more fully described.

These plates 15 of the clevis 14 are formed with longitudinal rows of spaced openings 20—20, those of one row being in staggered relation with those of the other, as clearly disclosed in Figure 1, and the openings of both plates being in registration with each other. Preferably one of the plates adjacent the center row of openings carries indicating numerals for indicating the degree of movement of the outer end of the lever 11 when the inner end thereof which car-

ries an opening 21 between the plates is moved in opposite directions within the clevis. The registration of the opening in the lever with the inner rows of openings will indicate the degree of movement of the outer end of the lever by one-half of the predetermined distance between the outer rows of openings, which is of course obvious.

When the opening in the lever 11 has been brought into registration with the predetermined registering openings in the plates 15-15 of the clevis, a cotter pin 22 or other similar locking means is passed therethrough for preventing the swinging of the lever.

Micrometric adjustments of the lever 11 may be secured by adjusting the connection between the eye bolt 12 and angle plate 7.

In carrying out the present invention the particular adjusting mechanism disclosed may be associated with the two endmost or all of the kicker wheels as desired, and in view of the foregoing description when considered in conjunction with the accompanying drawings it is believed by me that the operation and specific construction of such device will be readily obvious to those skilled in the art and even though I have herein shown and described the invention as consisting of certain detail structural elements it is nevertheless to be understood that some changes may be made therein without affecting the spirit and scope of the appended claims.

Having thus described the invention, what I claim as new and desire to secure by Letters Patent is:—

1. In a kicker wheel adjusting means for fruit grading machines of the kicker wheel variety including a sizing belt, and a driven kicker wheel arranged above the belt, a lever loosely attached at one end to a wheel mount, a pivotal connection between the lever at an intermediate point in the length of the latter and the machine frame structure in back of the wheel, a support, means at the rear end of the lever whereby the same may be secured in predetermined raised or lowered position, said means pend-

ent from and adjustable relative to said support.

2. In a kicker wheel adjusting means for fruit grading machines of the kicker wheel variety including a sizing belt, a plurality of swinging and driven kicker wheels and a machine frame unit above and in back of the wheels, a bracket rigidly bolted to the said frame directly in back of one of the kicker wheels, a lever pivoted intermediate its ends to said bracket and loosely connected at its forward end to the wheel mount, and means at the rear end of the bracket for facilitating the anchoring of the outer end of the lever in predetermined raised or lowered position, said means consisting of a clevis depending from the end of the bracket and pivoted thereto and between which the end of the lever is arranged, said clevis being formed throughout its length with spaced openings while said lever is formed with an opening for registration with predetermined openings of the clevis so that a pin may be passed therethrough.

3. In a kicker wheel adjusting means for fruit grading machines of the kicker wheel variety including a sizing belt, a plurality of swinging and driven kicker wheels and a machine frame unit above and in back of the wheels, a bracket rigidly bolted to the said frame directly in back of one of the kicker wheels, a lever pivoted intermediate its ends to said bracket and loosely connected at its forward end to the wheel mount, and means at the rear end of the bracket for facilitating the anchoring of the outer end of the lever in predetermined raised or lowered position, said means consisting of an eye bolt depending from the rear end of the bracket, a clevis pivoted to the eye of the bolt and depending therefrom, and formed at its sides with longitudinally spaced registering openings, the outer end of the lever being positioned through said clevis and having an opening therein for registry with predetermined openings of the clevis for receiving a locking pin.

In testimony whereof I affix my signature.

EDWIN M. WAYLAND.
